(57) **CLAIM**

The ornamental design for a digital multimeter including a remote display, the body for the digital multimeter including a remote display, and the head for the digital multimeter including a remote display, as shown and described.

DESCRIPTION

FIG. 1 is front elevation view of a digital multimeter including a remote display.

FIG. 2 is a left-side elevation view thereof.

FIG. 3 is a right-side elevation view thereof.

FIG. 4 is a back elevation view thereof.

FIG. 5 is a top plan view thereof.

FIG. 6 is a bottom view thereof.

FIG. 7 is a first perspective view thereof.

FIG. 8 is a second perspective view thereof.

FIG. 9 is a third perspective view thereof; and,

FIG. 10 is a fourth perspective view thereof with a support stand extended.
